CANDLE WICK

Albert T. Candy, Jr., Oak Park, Ill., assignor to
 Candy & Company, Inc., Chicago, Ill., a corporation of Illinois

Application February 5, 1934, Serial No. 709,721

10 Claims. (Cl. 67—22)

My invention relates to wicks, and more especially to candle wicks for candles used in sanctuary lamps. My wick is also adapted for use in oil burning lamps using upstanding or self-supporting wicks, especially in those sanctuary lamps where the liquid fuel is in a cylindrical container.

In solid candles (as well as in what might be termed "liquid candles") which are to burn slowly and for a long period of time, it has been customary to stiffen or reinforce the wick by weaving it as a tubular wick to be placed about a straight lead wire core or a split bamboo core.

One object of my invention is to provide a wick having the equivalent upstanding or self-supporting characteristics, but not requiring a core.

Another object is the provision of a stiffening for the wick which permits the use of a "self-consuming" wick without interfering with the successful functioning of the "self-consuming" feature.

Still another object is to bring a solid candle quickly to its normal operating condition with the proper depth of melted wax beneath the wick end without the objection of the body of melted wax—due to its expansion upon melting—raising the liquid level to a point so near the upper end of the wick as to provide an inadequate flame or perhaps even to the point of submerging the wick and thereby extinguishing the flame. I effect this object preferably by enlarging the capacity of the wick for a distance at its upper end to generate heat at a greater rate during the initial period of its burning.

The foregoing, together with further objects, features, and advantages of my invention are set forth in the following description of a specific embodiment thereof, and are illustrated in the accompanying drawings, wherein

Fig. 1 is a longitudinal section through a candle and sanctuary lamp therefor, the candle having a wick embodying a preferred form of my invention;

Fig. 2 is a greatly enlarged fragmentary section through the upper end of the unburned candle showing the upper end of the wick;

Fig. 3 is a somewhat similar enlarged fragmentary section but showing the wick and candle under normal burning conditions;

Figs. 4 and 5 are transverse plan sections taken on the lines 4—4 and 5—5 respectively, of Fig. 2;

Fig. 6 is a view similar to Fig. 1 but showing

a modified form of wick in normal burning condition, and

Fig. 7 is a view similar to Fig. 3 but showing the modified wick of Fig. 6.

In the drawings I have illustrated a candle, jacketed by amorphous cellulose, in a sanctuary lamp as shown in Patent No. 1,975,496 of October 2, 1934 issued on the application of Francis J. Barrett, Jr., Serial No. 677,547, filed June 26, 1933, on a sanctuary lamp and candle therefor. The candle 10 is jacketed in a closely fitting cylinder 13 of transparent flexible sheet material such, for example, amorphous cellulose. The candle is mounted on the central depression 15 of a supporting ring 14, which rests upon a pedestal base 20. The candle is surrounded by a glass cylinder 17, leaving an air space 29 between the jacket 13 and the glass tube 17. The upper end of the glass tube is covered by a cap 21, 22 seated upon the upper end of the tube and provided with an inwardly directed annular flange 24 meeting the upper end of the jacket 13 to seal off the air space 29. The cap is arranged to give an adjustable air intake through the regulating holes 28, the hot combustion gases leaving at the central aperture 27. I prefer, however, to dispense with any reinforcing ring at the top edge of the jacket 13.

The main wick 30, which may be of cotton, is formed of twisted or woven cotton strands, preferably of solid or non-hollow construction. The wick is made "self-consuming" by the usual expedient of incorporating one strand under greater tension than the others so that as the wick burns down the tensioned strand contracts more than the others, pulling that side of the wick over into the beginning of a curl to bring the tip of the wick laterally through the flame proper and into the free oxygen of the air so that the cotton of the wick will be entirely burned or consumed.

In sanctuary candles which are burned for long periods of time, usually seven or eight days, the size of the flame must be necessarily rather small in proportion to the bulk of the candle so that the candle will not be consumed too rapidly and, therefore, not last the full period required. As the wick must be self-supporting through an inch or so of melted wax immediately below the flame and as the cotton part of the wick is relatively small to cut down the flame size, it is very desirable to have the wick reinforced or stiffened. It has been usual to employ a split bamboo or straight lead wire core within a tubular wick. Such construction, however, did

not free the wick from the stiffening effect of the reinforcement within the vertical distance of the flame to permit the normal self-consuming feature of the wick to function.

5 Instead of putting the reinforcing bamboo strip as a core within the wick, I apply the bamboo strip 31 externally of the wick and side by side with the wick. The strip 31 and the wick are held together by a fine lead wire 32 wrapped spirally about the surface of the wick, leaving preferably about three thirty-seconds of an inch space between convolutions, this spiral wrapping extending the entire length of the wick.

10 15 The bottom end of the wick is held by the projections 33 struck up from a sheet metal disc 34, which forms a supporting base for the wick. In the instance of a solid candle the supporting disc 32 holds the wick upright when 20 the candle has burned down to a level where the body of the candle itself could no longer adequately support the wick. In the instance of lamps where a liquid rather than a solid fuel is substituted in the shell 13 or other cup, the 25 supporting disc 34 may be relied upon to hold the wick upright at all times.

30 Referring to Fig. 3, the heat of the flame melts the externally wrapped wire 32 down to the level of the melted wax of the candle. This fully 35 frees the wick, above the base of the flame, from the stiffening influence of the bamboo strip 31 and of the spiraled wire itself which also has a considerable stiffening effect even apart from the strip 31. This permits the tight 40 strand in the wick, when subjected to the heat and charring effect of the flame, to curve the upper end of the wick over to the lateral edge of the flame well below the tip of the flame so that the curved end of the wick can have free access to the oxygen of the air and burn or consume 45 the wick entirely without leaving any charred remains which might smoke or fall down into the liquid wax and gradually dirty it.

50 I might explain that in the instance of those wicks where bamboo reinforcing strips constituted a central core for the wick, the wick acted as a shield or jacket for the strip so that it would not be burned and hence free the wick for the self-consuming bending at a level sufficiently below the tip of the wick. The wick 55 and the bamboo extending practically to the tip of the flame made a smokier flame. In those wicks where the stiffening core was a comparatively heavy lead wire, the lead core would similarly be shielded by the jacketing wick and the core would not melt at the base of the flame but at a point near the tip.

60 Even where the fabric wick is not of the self-consuming type, there is an important advantage in mounting the reinforcing strip externally of the wick rather than as a central core. In practice commercial split bamboo—the usual reinforcing strip material—is not of uniform cross section. Some will run larger than others. A 65 given tubular fabric wick filled out to one diameter by a bamboo core will have a larger capacity than an identical wick filled out to a lesser diameter by a bamboo core which happens to run slightly smaller in cross section. In production this results in lack of uniformity in flame size and rate of consumption of the candles. 70 Variations in cross sections of the bamboo strips, when applied externally, have practically no effect on the capacity of the wick, size of flame or rate of consumption. If the fabric wicks

are substantially uniform in production—which they are—the performance of the candles will be uniform, in so far as the wick is concerned, with my externally applied reinforcing strips.

5 In Figs. 6 and 7 I have shown a modified form of wick where the wick is similarly "solid" and non-tubular but where the split bamboo reinforcing strip 31 is omitted, the fine lead wire 32 being spirally wrapped around the wick only. Either with the external split bamboo reinforcement 31 of Fig. 2, or the spiraled wire alone of 10 Fig. 7, my wick has a greater flexibility within its elastic limit than is the case with wicks having a lead wire core. There is thus less danger 15 of the wick being permanently deformed upon slight bending incident to shipping, handling and assembly.

15 I now refer to another feature of my wick which, while illustrated as applied to a wick using external bamboo reinforcing strip, may be 20 incorporated with the wick of Figs. 6 and 7 using only a spiraled wire, or even to wicks having no formal reinforcement. The upper end of the wick is augmented by an auxiliary or 25 collateral wick 30' which, as shown in Fig. 2, 30 may conveniently be placed on the side of the bamboo reinforcement 31 opposite the main wick 30 before the spiraled wire 32 is applied, so that the wire serves to bind together the main wick, the bamboo strip and the collateral wick. The 35 effect is to give the wick approximately double capacity for a short distance at its upper end. The vertical distance of this increased capacity of the wick, as thus secured, extends from the upper end of the wick, through the distance by 40 which the wick usually initially protrudes and also through the distance represented by the height of the central mound-like portion 10a of lesser diameter of wax at the upper end of the candle.

45 When the wick is initially lit, the flame burns with approximately double the normal size because of the double capacity of the wick. The candle material for consumption of the wick during the operativeness of its double size comes primarily from the central portion 10a of reduced diameter. The greatly increased size of the flame causes a more rapid heating and melting of the body of the candle to melt the wax down to the normal burning depth of liquid 50 wax, as represented by Fig. 3. Because the melting of the requisite depth of wax is accomplished more quickly due to the increased size of the initial flame from the double capacity wick, while the linear rate of consumption of the 55 wick is not materially increased, the result is that the full normal burning depth of liquid wax is secured before the wick has been consumed down to the point where the rise in level 60 of the liquid wax, due to its great expansion upon melting, can rise to the point of submerging the wick and extinguishing the flame. Nor does the rise in the level of the liquid, due to its great expansion upon melting, come so close 65 to the upper end of the wick as to cause an inadequate flame for some time during the initial burning of the candle.

70 I might explain that this problem of avoiding the submerging of the wick due to the expansion of the wax upon melting, is one which becomes increasingly acute as the diameter of the candle increases in proportion to its wick capacity, as is the case with long-burning candles and especially where, as is the case with the insulated 75 sanctuary lamp here shown, the heat of the

flame is retained against rapid dissipation with the result that the candle carries a much deeper layer of melted wax and, consequently, a greater rise in liquid level upon the melting of the wax 5 to such liquid depth.

While I have illustrated these specific embodiments of my invention, I contemplate that variations and changes may be made thereover without departing from the spirit or scope of 10 my invention. For example, other metals or alloys of low fusing point may be used in substitution for the lead mentioned and a wire may be applied other than as a simple spiral alone. For example, a left-handed spiral of wire might 15 be wrapped upon the initial right-hand spiral, or a plurality of strands might be woven about the wick as a braided jacket.

I claim:

1. A candle wick comprising a self-consuming 20 fabric wick, a reinforcing strip extending therealong externally thereof, and a fine wire, fusible at the temperature at the base of the flame, openly wrapped about the fabric wick and strip for holding them together.
2. A candle wick comprising a self-consuming 25 fabric wick, a reinforcing strip extending therealong externally thereof, and means for holding the fabric wick and strip together, said means being rendered inoperative above the base of 30 the flame by subjection to the temperature of the base of the flame.
3. A candle wick comprising a self-consuming 35 fabric wick, a reinforcing strip of combustible material extending side by side therewith, and a connecting member for holding the strip to the fabric wick, the connecting member being fusible at the temperature of the base of the flame.
4. A burning candle comprising a cylindrical 40 body of solid wax, a layer of melted wax thereabove, a fabric wick extending upwardly through the solid and melted wax and protruding thereabove, a flame at the upper end of the wick, a reinforcing strip of combustible material extending side by side with the fabric wick externally 45 thereof, and a wrapping of wire of a metal, fusible at the temperature of the base of the flame, about the fabric wick and strip to secure them together, the wire extending through the solid and melted wax up to but not substantially into the body of the flame, the fabric wick having a tight strand to render it 50 self-consuming.
5. A fabric candle wick of substantially uniform capacity throughout its length except that 55 downwardly from one end for a substantial dis-

tance but a minor portion of its length it is of substantially increased conducting capacity.

6. A candle comprising a cylindrical body of wax having a wick extending centrally therethrough, and protruding therefrom, the protruding end of the wick being of increased capacity, relative to the body of the wick, the region of increased capacity extending downwardly into the top end of the wax for a substantial distance. 5

7. The combination of a cylindrical solid candle, a lamp therefor jacketing the candle and its flame, the upper end of the candle having a protruding mound-like portion of reduced diameter, and a fabric wick extending centrally 15 through the candle and protruding at the upper end thereof beyond said mound portion, said protruding portion of the wick and the portion of the wick extending through the height of said mound-like portion being of substantially 20 greater capacity than the remainder of the candle for providing a flame of increased size and rate of wax consumption during the initial burning of the candle. 10

8. A composite candle wick comprising a self- 25 consuming fabric wick, a reinforcing strip of bamboo extending therealong externally thereof, and a wrapping of wire of a metal fusible at flame temperature for holding the fabric wick and strip together, and an auxiliary fabric wick 30 extending along the first-mentioned wick and the strip downwardly from the upper end of the composite wick for only a minor portion of the length thereof and also embraced by said wrapping, whereby the composite wick is of increased 35 capacity at its upper end. 30

9. A composite wick for candles comprising a long substantially straight length of strand-like fabric wick, a reinforcing strip of flame- 40 consumable material extending side by side with, and externally of, the fabric wick, and a wrapping about the fabric wick and strip for holding them assembled, the wrapping being rendered inoperative by the temperature of the base of the flame. 45

10. A composite wick for candles comprising a length of self-consuming fabric wick, a strip of split bamboo side by side with, and externally of, the fabric wick, and a fine wire, fusible at the temperature of the base of the flame, 50 wrapped about the fabric wick and the strip to hold them in assembled relation but permitting the wick and strip to pull apart above the base of the flame. 50
